CLAIM

U.S. PATENT DOCUMENTS

The ornamental design for a semiconductor element, as
shown and described.

DESCRIPTION

D298,327 S * 11/1988 Kimura D14/114
D356,291 S * 3/1995 Kawamura D13/110
5,548,485 A * 8/1996 Bethurum et al. 361/737
D375,937 S * 11/1996 Mergenthaler et al. D13/110
D376,133 S * 12/1996 Kerklaan D13/182
D379,350 S * 5/1997 Kerklaan D13/182
D421,597 S 3/2000 Oba et al.
D421,967 S 3/2000 Oba et al.
D427,159 S * 6/2000 Oba D13/182
D432,505 S * 10/2000 Oba et al. D13/182

FIG. 1 is a perspective view of a semiconductor element
showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
